UNITED STATES PATENT OFFICE.

LA VERNE W. NOYES, OF CHICAGO, ILLINOIS.

GRAIN-BINDER.

SPECIFICATION forming part of Letters Patent No. 366,502, dated July 12, 1887.

Application filed December 23, 1885. Serial No. 186,926. (No model.)

To all whom it may concern:

Be it known that I, LA VERNE W. NOYES, a citizen of the United States, residing at Chicago, in the county of Cook and State of Illinois, have invented certain new and useful Improvements in Grain-Binders, which are fully set forth and described in the following specification.

This invention relates to automatic grain-binders; and it comprises improved mechanism for packing the grain and improved means of actuating the same; improved mechanism for adjusting the gavel-supporting floor or butt-evening board to correspond with the length of the grain; improved mechanism for operating the compressor; improved mechanism for dividing the gavel from the flowing grain and retaining the latter out of the path of the needle; improved means for causing the binding mechanism when it starts to disconnect from the driving-power the conveying and packing mechanism; improved mechanism for stripping the dischargers; an improved form of trip, and improved structure of the bearings for the binder-gear train.

In the drawings, Figure 1 is a plan of the binder, the conveyer, sickle, and drive-wheel being shown sufficiently to show their relative positions. Fig. 2 is an outer elevation of the parts located outside of the vertical plane through the line x x on Fig. 1. Fig. 3 is an elevation of the parts located inward from said plane x x , the same being seen from the outer or drive wheel side, the frame and the grain-supporting ledge being cut by said plane and shown in section. Figs. 4 and 5 are detail plans of the compressor and its connections with the needle, the former showing the position of said parts before the needle starts forward, and the latter showing their position at the instant the needle starts back. Fig. 6 is a section through y y , Fig. 5. Fig. 7 is a section through z z , Fig. 5. Fig. 8 is a plan of the clutching mechanism which connects the conveyer-driving train with the driving power and of the levers which operate it. Fig. 9 is a vertical section through n n , Fig. 8. Fig. 10 is an enlarged elevation, and Fig. 11 an enlarged plan, of the dog which engages said clutching mechanism. Fig. 12 is a plan of the trip and the disk which carries it. Fig. 13 is a section through m m , Fig. 12. Fig. 14 is a

plan of a part of said trip, showing the serrated shoulder by means of which it is made adjustable. Fig. 15 is a vertical section through the line v v , Fig. 1. Fig. 16 is an elevation of the parts shown in Fig. 9. Fig. 17 is a vertical section through the shaft and wheels therewith connected, whereby the packer-wheel is driven. Fig. 18 is an elevation showing in detail the binder-clutch. Fig. 19 is a perspective of the binder-frame and the packer-frame pivoted thereon, all the other mechanism being removed, the point of view being at the rear on the grain side. Fig. 20 is a vertical section through o o , Fig. 1. Fig. 21 is a perspective of a pinion which is journaled in the packer-frame. Fig. 22 is a detail elevation of the stubble side of the arm in which the needle rock-shaft is journaled, showing a bracket secured thereon for certain purposes related to the action of the compressor.

The said figures illustrate my invention as applied to a harvester and binder which accumulates and binds the grain standing on end; and many of the details are applicable only to such a machine.

The general structure and action of the machine are as follows: The grain severed by the sickle is lodged standing on end upon the grain-supporting ledge B in the rear of the sickle, and leans against and is carried stubbleward by the leaning conveyer B' , being carried standing around the delivery end of said conveyer and back over the grain-supporting ledge, which extends back, forming a floor ending at the binder-frame. It is kept from falling stubbleward against the gearing by the upright guard or sheath W , which is secured to the platform, and extends from a point stubbleward from the heel of the sickle, rearward and stubbleward toward the binder, and forms the boundary on the stubble side of a grain-receptacle at the discharge end of the conveyer. It is here received by the packers and packed, still standing on end, in the binder, against the trip, which protrudes horizontally across the bundle-space. When the trip is actuated and the binding mechanism comes into action, the conveyer stops and the needle enters from the side toward the standing grain, moving in substantially a horizontal plane, encircles the bundle, which still stands on end, and when the binding is completed the dischargers, moving

BEST AVAILABLE COP

2

366,502

in horizontal planes, eject the bundle to the rear and stubbleward, such having been the course of the grain from the point where it passed around the end of the conveyer.

5 In detail the mechanism is as follows:

A is the drive-wheel; A', the main gear-rim thereon.

A² is the main driving-pinion, receiving motion from the gear-rim A', and communicating to the same through its shaft a² and the bevel-gears A³ and A⁴ to the binder mechanism and to the conveyer mechanism, respectively. The conveyer-driving train comprises the said bevel-gear A⁴ and the bevel-gear A¹⁰, meshing with it and fixed upon the vertical shaft a¹⁰, carrying at the lower part below the frame the gear-wheel A⁴, clutched to it by mechanism hereinafter described, and the horizontal gears A¹² A¹³, which lie underneath the sheathing b, Fig. 3, of the conveyer-floor or grain-ledge B, the last of said gears being the last in the conveyer-driving train, the conveyer-driving roller having its shaft connected to and revolved by it. The mode of this connection is not herein shown in full, but is made the subject of my application No. 186,925, filed December 28, 1885.

The binder-frame is secured to the rear of the grain-ledge or conveyer-floor, and comprises the two horizontal arms C' and C⁵, connected by the cross-neck C² and upright bar C. It comprises also the upright arms C⁴ and C⁵—the former to afford bearing for the needle rock-shaft, and the latter to afford bearing for the knotter-actuating shaft. It comprises also the brace or extension C', reaching grainward at the forward end, designed to afford secure attachment to the plank which constitutes the conveyer-support. It is also braced on the stubble side by the arm W of the harvester-frame. Upon a stud-axle on said extension C' is journaled the horizontal gear-wheel A⁴, which meshes with and is driven by the horizontal gear A³. To an upwardly projecting lug, c', of the arm C' of the binder-frame is pivoted the packer-frame D, and at the forward end of the arm D' of said packer-frame is journaled the pinion A¹⁵, said pinion being formed with a hub, a¹⁵, which constitutes its axle, and said hub having at the lower end the flange a¹⁵⁰, to retain it in its journal-box d', in which it is first inserted by removing the cap d¹⁰. Said pinion has a central opening extending through its hub, said opening being oblong in form and adapted to receive the flat shaft A¹⁶, which fits said opening quite loosely, particularly being slightly narrower than the length of the said opening. Said flat shaft A¹⁶ is forked at the lower end and its prongs a¹⁶ 60 stride the stud-axle a¹⁴ and enter, respectively, the sockets or apertures a¹⁴⁰ a¹⁴⁰ in the web of the gear-wheel A⁴.

Upon the packer-frame D is journaled the packer-wheel E, which has the peripheral gear-rim E', meshing with the pinion A¹⁵, and by that means the said packer-wheel receives motion. Said gear-rim is preferably protected

by the flange e' on the upper side. Upon said packer-wheel are pivoted the packers E² E², which are preferably bell-cranks pivoted at 70 their angles near the rim of the wheel E on the upper side, having at the end of one arm an abutment preferably in the form of an anti-friction roll, c², and having the other arm adapted to enter and actuate the grain. To 75 the packer-frame, under the packer-wheel, is fastened or made integral the cam D², which has the surface d² concentric with the wheel E for a distance somewhat greater than the intervals between the packers, and adapted to 80 engage the abutments c², the web of the wheel E being reduced to a mere skeleton and the said abutments protruding down through the interspaces, and standing thus in the plane of the said cam on the lower side of the wheel. 85

The packer-frame D is cranked grainward, as seen in Figs. 1 and 3, the cranked portion D³ being so formed as to allow space for the play of the needle F. Above said cranked part it is bent stubbleward while extending 90 upward, and its upper arm, D⁴, bears against the upper bar, C¹⁰, of the inner grain-wall, C, of the binder. Said bar C¹⁰ is notched to receive said arm D⁴ and detain it at any desired position. The stiffness of said arm or of the 95 entire frame D is sufficient to keep it in the notches, and its elasticity is sufficient to allow it to be sprung out when desired, and no special device is therefore provided for these purposes. By means of the arm D⁴, operating 100 as a handle for the packer-frame, the latter may be rocked over its pivot on the lugs c' and the direction of the planes of action of the packers adjusted as desired.

The floor H' of the binder corresponds in part 105 to the butt-evening board of a binder wherein the grain is bound prostrate. Said floor is connected to the binder-frame by the link H, as wide as said floor, and pivoted at the rear side of the cross-neck C², and connected at the other end to the floor H', which is substantially horizontal. Said link H forms an approach from the conveyer-floor to the horizontal floor H' of the binder, adjusting itself automatically to the position of the latter. To the rear end of the floor H' is fastened rigidly the cam H¹⁰, which extends upward to a point considerably above the plane of the needle, being bent rearward between its ends to allow room for the play of the compressor. To the upper 115 part of the binder-frame, most conveniently to the lug c¹¹, fixed on the rear bar, C¹¹, of the grain-wall C, is pivoted the bell-crank lever H², and to one of the arms H²⁰ is pivoted the said arm H¹⁰ of the binder-floor H'. The other arm, H²¹, is connected to the arm D⁴ of the packer-frame D, whereby the movement of the arm D⁴ simultaneously adjusts both the packer-frame and the binder-frame. The connection 120 may be made, as illustrated, by the chain H³. The arm D⁴ is preferably bent at the upper part, so as to diverge from the arm H²¹ in the most ordinary positions of the said arms, and the distance between said arms may be varied,

130

135

and thereby the relative positions of the packers and the floor H' may be adjusted by securing the chain H^3 at different points on said arms, and for that purpose the said arms may be provided with series of holes h^1 and h^2 . The same result may be effected by shortening the chain H^3 . The floor H' has the flange or side guard, H^1 , at the inner side, to keep the grain on the said floor. It is found most convenient to secure the arm H^{10} to the floor by riveting it to the side guard, H^1 . The length of the arm H^{10} should be such that the distance from the hinge h' , where the link H joins the floor H' , to the pivot h^2 at the junction of the arm H^{10} and the arm H^{20} of the bell-crank lever H^2 shall be approximately equal to the distance from the junction h of the link H with the frame to the fulcrum of the bell-crank lever H^2 , and the length of the arm H^{20} of said lever should be approximately equal to length of the link H . Such relation will insure that the floor H' , if horizontal in one position, will be horizontal in all positions to which it may be adjusted by the lever H^2 , the link H and the arm H^{20} being in effect parallel links connected each at one end to the same rigid structure—the binder-frame—and having their other ends connected, as by a link, in the position of the dotted line from h' to h^2 . All positions of such a link will be parallel with each other, and the same would, therefore, be true of any other part of the rigid structure connected at the pivots h' and h^2 . By locating the fulcrum of the arm H^{20} , which serves as one of the parallel links to connect the floor to the frame, as described, so that a line from said fulcrum to the pivot h is above the highest position to which it is necessary to raise the link H in adjusting the floor H' , I escape a difficulty which is found to exist when it is placed lower than as above stated—namely, that after the link H reaches a position coincident with the line connecting the pivots of the two links further attempt to raise the floor will cause only the rear end of it to rise, since the link H will fall instead of rising, such motion serving equally as well as the contrary one to accommodate it to the rising movement of the other link and being compelled by gravity.

The binding mechanism receives motion from the bevel-gear A^3 , which meshes with and drives the bevel-gear A^{30} on the forward end of the oblique shaft a^{30} , which has loose upon it, but adapted to be clutched to it at the rear end, the bevel-gear A^{31} , which meshes with and drives the bevel-gear A^{32} , fixed on the lower end of the vertical binder-shaft a^{32} , which is journaled in the vertical arm C^3 of the binder-frame, and carries at the upper end, above its journal-bearing in said frame, the knotter-actuating wheel A^{33} , whose detail structure is not a part of my invention and will not be described herein.

For reasons which will hereinafter appear it is desirable that the space between the arm C^3 of the binder-frame and the shaft a^{30} should

be free from any obstructions for a considerable distance from the vertical arm C^3 ; hence no projection can be provided extending from said arm to afford a bearing for the shaft a^{30} , except near the forward end of said shaft, where it has the bearing c^3 . For the rear end of said shaft a bearing is provided by forming the yoke A^{34} , having the sleeve A^{340} , by which it is journaled on the shaft a^{30} , above the wheel A^{32} , and in the side of said sleeve the oblique step bearing or socket A^{341} for the shaft a^{30} , and in line with said oblique step-bearing, at the other end of the bow of the yoke, there is the further bearing A^{342} for said shaft. Between said bearings A^{340} and A^{341} the bevel-pinion A^{31} is placed loose on the shaft, as stated. The mechanism for clutching said gear A^{31} to the shaft does not form any part of the present invention and is not shown or described in detail. It consists of a dog, a^{310} , pivoted on the face of the bevel-pinion A^{31} , eccentrically thereto, said dog having an abutment, a^{312} , adapted at one position of the dog to be engaged by the lugs a^{300} on the shaft a^{30} , the spring a^{311} being provided to force the dog into such position, the trip-lever G being provided with a finger, g , to engage the dog to disengage it from the lugs. The trip stands at rest in a position to hold the dog out of engagement, and is forced away from such position by the pressure of the bundle, and this caused to release the dog and permit it to become engaged with the shaft a^{30} , and thus communicate motion from said shaft to the pinion A^{31} . To the shaft a^{32} is secured the disk A^{35} , immediately below the lower end of the arm C^3 of the binder-frame, and to it are secured the trip G and the lower or butt-actuating discharger, K .

By reason of the standing position of the grain I have found that especially in tall or overripe grain there is a tendency for the heads to bend over and hang down beyond the trip when that part is a single arm, and that in such case, when the trip revolves, it gathers such overhanging heads and carries them around with it. To prevent this, I have provided the trip with a horizontal extension to the rear G^{10} , giving to the trip the form of a broad blade or shelf, upon which the heads of the grain will rest when they overhang, as described, and wide enough so that the heads will not reach beyond it and hang down far enough to be engaged and drawn around by it. In practice I find it safe to make this blade in skeleton, as illustrated.

For convenience of adjusting the trip to vary the size of the bundle without changing its compactness, I have made the arm in two pieces, G' and G^2 , with an adjustable joint at g , two radially serrated or convoluted shoulders being clamped together by a bolt in a familiar manner, the bolt being loosened to vary the adjustment.

The reason and necessity for the construction which avoids obstruction between the shaft a^{30} and the frame-arm C^3 is, that the trip and the discharger must revolve through that

space when they are located, as shown, above the gear-wheel A^{32} . I find it desirable to locate them above said wheel, in order to obtain great enough range for the adjustment of the 5 binder-floor or butt-evening board H' , for the trip should be as nearly as possible in the plane of the needle, and if the trip is low the needle is likewise required to be low, and the range of adjustment for the floor between the 10 needle and the ground is correspondingly limited. The same reason that requires the guard at the rear of the trip makes it necessary to take special precaution to prevent the heads of the grain in the bundle from hanging over the dischargers and being carried around with them, and this is done by giving to the stripping device the form illustrated, which is a frame, L , having stripping-bars $L' L'$ between the dischargers—one near to each discharger— 15 and having also a stripping-bar, L^2 , close above the upper discharger, and a stripping-bar, L^3 , close below the lower discharger. The upper and lower bars are made of one piece of iron and form the frame-work. The upper, L^2 , is 20 extended forward past the entire gaveling-space of the binder, above the breast-plate a considerable distance, and is then bent down and secured to the arm C^3 of the binder-frame. This forwardly-extended part serves to sustain 25 the grain-heads and keep them from falling over and becoming entangled with the knotter mechanism. The intermediate stripping-bars, $L' L'$, at one end are secured to the cross portion l of the frame, and at the other end are 30 secured to the breast-plate M .

The needle N is secured to the upper end of the vertical rock-shaft n' , which is journaled in the vertical arm C^4 of the binder-frame. It derives motion from the gear-wheel A^{32} by 35 means of the link N' , connected at one end to the wrist-pin a^{320} on said gear-wheel A^{32} , and at the other end to one end of the lever N^2 , pivoted at n^2 on the frame, and from the other end of which the link N^3 extends to the lever-arm N^4 on the lower end of the needle rock-shaft. The mode and means of communicating motion to the needle hereinabove described is not herein claimed, but is claimed in my application No. 170,143, filed June 29, 40 1885.

The lever N^2 is employed as the means of disengaging the gear-wheel A^4 from the shaft a^4 and so stopping the conveyer and packers when the binder starts. The mechanism for 45 this purpose is as follows: Upon the rear edge of the plank which forms the grain-supporting ledge B is fixed on suitable slide-bearings the sliding dog P , having the hooked end p^2 protruded down behind the lever N^2 , and in 50 position to be engaged thereby as the lever retreats at the close of the action of the binder. Said dog is provided with the spring p' , tending to thrust it in the opposite direction from that in which said lever will move it. To the 55 lower end of the shaft a^4 there is secured fast the cam-wheel A^{400} , having four cam projections, a^{400} . For convenience of affording an

easily-dressed bearing for the gear-wheel A^4 , this cam-wheel A^{400} is produced upward in a sleeve, A^{401} , around the journal-bearing a of the shaft a^4 , and outside of this sleeve is journaled the gear-wheel A^4 ; which rests upon the upper surface of the cam-wheel A^{400} . Below said cam-wheel, loose on the shaft a^4 , is the ratchet-wheel A^{410} , which is supported by the 70 disk or washer A^{411} , which is itself supported by a linchpin, a^{411} , put through the shaft a^4 below said washer. The web of the ratchet-wheel A^{410} has the slot a^{410} . To the undersurface of the gear-wheel A^4 is pivoted the driving-link A^{412} , and the other end of said link is made to engage in said slot a^{410} . Said link has the abutment a^{412} , which is preferably provided with an anti-friction roll, to be engaged by the cam projections a^{400} of the cam-wheel A^{400} . The direction of the slot a^{410} is eccentric to the wheel A^{410} , so that when the engaged point of the link A^{412} stands at the end of the slot nearest the center of the wheel the abutment a^{412} is in position to be engaged by the cam-wheel A^{400} , and when it stands at the other end of said slot said abutment is out of range of said cam-wheel. The first-stated position is shown in Fig. 8, and in this position the cam A^{400} engages the link A^{412} , thereby driving the 85 gear-wheel A^4 , and through it the conveyer and packer. When the binder starts, the lever N^2 is drawn by the link N' toward the ratchet-wheel A^{410} , and the dog P is forced by the spring p' into engagement with the ratchet-wheel A^{410} and arrests its revolution. The link A^{412} , continuing to move, has its end engaged in the eccentric slot a^{410} , carried out from the center, until the abutment a^{412} is released from the cam-wheel A^{400} , whereby the 90 gear-wheel A^4 is disconnected from the driving-power of the shaft a^4 , and the conveyer and packers come to rest. When the lever N^2 at the completion of the action of the binder returns to the position shown in Fig. 8, the 95 sliding dog P is withdrawn from engagement with the ratchet-wheel A^{410} , and the latter, resting upon the washer A^{411} , is started by the friction of the latter, and, revolving a distance equal to the length of the slot a^{410} , forces the link A^{412} in toward the cam-wheel A^{400} and brings the abutment a^{412} again into engagement with the cam-wheel A^{400} , and thereby the motion of the gear-wheel A^4 and the subsequent train is renewed. 100

It should be observed that the action of the packers will continue for a brief time after the needle starts, and that circumstance is of some importance in view of the action of the divider R , whose structure and operation I will now 105 describe. It is in the nature of a horizontally-swinging gate hinged about in line with the point where the needle pierces the inner grain-wall of the binder, the hinge-axis therefore being vertical, and standing when at rest 110 within the arc through which the needle plays, and close against or even inward from the inner grain-wall, and moving at the instant the needle starts outward across the gaveling- 115

space until it stands directly across it, barring the passage from the conveyer to the binder. In detail, as illustrated, it comprises the rock-shaft R' , pivoted or journaled at two convenient points, both above the plane of the needle on the binder-frame, and most conveniently on that portion of it which is made up of the horizontal bars which form the inner grain-wall. Said rock-shaft has fixed to its lower end, and standing quite close above the plane of the needle, the rigid arm R^2 , and higher up preferably another arm, R^{20} , which I find may be made yielding. To the rigid arm is connected quite near the rock-shaft the link R^3 , the other end of which is pivoted to the needle at a point so situated that the starting of the needle will give as nearly as possible a direct thrust to the said link, so that the motion of the arms R^2 and R^{20} , constituting the divider-gate, may be as prompt as possible, and that said gate may close across the gaveling-space before the needle has made any considerable advance thereinto. This motion will have occurred before the packers have ceased their action, and since the said gate and the packers are moving in opposite directions through the same body of grain they will separate it and tend to create a clear path for the needle. However, regardless of the action of the packers, the sweep of the arms R^2 and R^{20} being past the vertical line of the needle-point from a position inside its arc to a position outside the same, they will carry the grain back over its point, and thus leave a clear space for it to pass. When the needle retreats, the action of the divider is reversed and the path of the grain is again opened.

The mechanism for compressing the bundle is as follows: Pivoted to the needle eccentric to its rock-shaft is the compressor-link S , the pivot-bolt s being of considerable length vertically, so that it sustains the compressor-link and the compressor in horizontal position without other support. The link S has a tail, S' , which is extended back from its pivot into position to collide with the back edge of the needle. The rear end of the compressor-link S is expanded laterally to form the arm S^2 , to the inner end of which is pivoted the compressor S^3 , which is adapted to vibrate horizontally over said arm S^2 , and to afford it support in all positions said arm has its outer end broadened, forming the portion S^{20} . A stop-shoulder, S^{21} , is provided on the upper surface of said link, and the compressor has a corresponding shoulder, S^{31} , adapted to stop against the said shoulder on the link. Both said shoulders are pierced to admit the threaded link S^4 , which has a head to stop it behind the shoulder S^{31} , and has coiled about it in front of the shoulder S^{21} the spring S^5 , stopped between said shoulder at one end and the nut S^{10} at the other end. From the arm C^4 of the binder-frame is extended the bracket C^6 , and in the end of it is placed the short rock-shaft S^6 , which has a weighted lever-arm, S^7 , depending from it, and an erect lever-arm, S^8 , standing up behind the inner

edge of the compressor-link S , and constituting a stop against its lateral vibration. The bearing of said rock-shaft S^6 is provided with a stop, c^6 , which prevents or limits the motion of the depending arm S^7 to the rear, but permits it to move freely forward, and having a reverse effect upon the action of the erect arm S^8 . The rocking of the needle as it moves to encircle the bundle causes the compressor-link carrying the compressor to slide forward, bearing against the erect arm S^8 , until the needle reaches its limit. In this action the bundle is compressed, and the compressor has yielded away from the needle somewhat, the shoulders S^{21} and S^{31} being separated as the spring S^5 has yielded to the strain upon it. When the needle starts to retreat, the erect arm S^8 will be rocked backward by the friction of the back edge of the link S against it; or, to insure certainty of action, a slight notch may be provided in the edge of the link to engage the said erect arm, which being so rocked out of the way of the said link, the latter, carrying the compressor, will swing horizontally inward, carrying the compressor out of the path of the bundle, which is then ejected by the discharger. The needle, now retreating, at the next instant comes into collision by its back edge with the tail S' of the link S , and the latter is again carried into its initial position.

The general structure of the machine herein described and shown—viz., the standing conveyer, the horizontally-operating needle packers, trip, and discharger, the adjustable packer-frame and the connected and simultaneously-adjustable binder-floor, the system of links and levers by which the motion of the needle is derived from the binder-shaft a^2 , and the compressor pivotally connected to the needle and stopped on the frame during the binding process and released and allowed to yield back out of the path of the bundle as the needle commences to retreat—is the subject of my applications filed June 29, 1885, Serial Nos. 170,142 and 170,143, and these features are not herein claimed, broadly.

I claim—

1. In combination with the conveyer moving the grain standing on end toward the drive-wheel, the binder-receptacle located rearward from the line of delivery of the conveyer, the conveyer-driving train located under the path of the grain from the conveyer to the binder-receptacle, and the packer-driving train having its first wheel located grainward from the path of the grain into the binder and deriving motion from the conveyer-train, and the packers actuated by said packer-driving train and operating above the binder-floor, substantially as set forth.

2. In combination, the gear-wheel A^4 , having the apertures a^{10} , the pivot frame, and the pinion journaling an oblong axial aperture which enters at one end wheel and at the other

pinion, substantially as and for the purpose set forth.

3. In combination with the needle, the compressor-link pivoted thereto and reciprocated thereby, the compressor carried and sustained solely by said link, a movable stop-bearing on the frame, on which the compressor-link reciprocates, engaged by the compressor-link at its outward movement, and thereby moved out of the plane of motion of said link, to permit the latter to yield away from the path of the bundle, substantially as set forth.

4. In combination with the needle and the compressor-link pivoted thereto and reciprocated thereby in a horizontal plane, and the compressor carried by said link, the horizontal rock-shaft S^6 , having bearings rigid with the frame, and having the lever-arm S^{61} , forming a stop-bearing for the compressor-link while it reciprocates in one direction and engaged by it in the opposite motion, and having the weighted lever-arm S^{60} , and provided with a stop rigid with its bearing, to limit its rocking in one direction, substantially as set forth.

5. In combination with the needle whose axis is vertical and plane of movement horizontal, and the compressor-link pivoted thereto and reciprocated thereby in a horizontal plane, the compressor pivoted and wholly sustained on said link and vibrating horizontally over the same, said link having the horizontal extension S^{62} , to afford support for the compressor in its said vibration, substantially as set forth.

6. The packer-frame pivoted to the main frame, and having the rigid lever-arm to adjust and secure it in relation to said frame, the binder-floor, the link connecting it to the main frame, the arm rigid with said floor and extended away from the plane thereof, the lever pivoted on the frame having one arm substantially equal and parallel with the link and connected to the rigid arm of the floor, and having the other arm connected to the packer-frame arm, all combined and operating substantially as and for the purpose set forth.

7. In combination with the pivoted packer-frame adjustable in a vertical plane about its pivot, the binder-floor adjustable to different heights and connected to said adjustable packer-frame, said connection being adjustable to vary the distance between the floor and the frame, substantially as set forth.

8. In combination with the adjustable packer-frame and the adjustable binder-floor, the lever pivoted on the frame and connected to the floor-arm to adjust the floor, diverging from the packer-frame arm, a chain connecting said arms and adjustable to different points on both, whereby the floor and packers may be relatively adjusted without varying the relation between their respective movements in relation relatively to the remaining

part of the binder-floor, the link

connecting it to the frame, the rigid arm extending from said floor, and the lever-arm connecting said rigid arm to the frame, the said link and lever-arm being substantially parallel and equal in length.

10. The horizontal binder-floor, the link, substantially equal in width, connecting it to the frame and constituting an adjustably-inclined approach to said floor, the arm rigid with and upwardly extended from said floor, and the lever-arm connecting said rigid arm with the frame, the lever-arm and the link being substantially equal in length and parallel.

11. In combination, substantially as set forth, the needle moving horizontally to encircle the upright bundle and the horizontal trip having the extension to form a guard to support overhanging grain on the side toward the discharge.

12. In combination with the horizontally-operating needle, the binder-shaft a^{22} , having its driving gear-wheel at the lower end and the knotter-actuating wheel at the upper end, and the trip-carrying disk rigid with said shaft above the driving gear-wheel, substantially as set forth.

13. The shaft a^{10} , and the gear-wheel A^{41} , cam-wheel A^{400} , and ratchet-wheel A^{410} , concentric with said shaft, the cam-wheel being fixed to it and the other two of said wheels being loose about it, the ratchet-wheel having the eccentric slot a^{410} , the link A^{412} , pivoted to the gear-wheel and engaging in the said slot in the ratchet-wheel, and having an abutment to be engaged by the cam-wheel, and the dog P , to engage and detain the ratchet-wheel, all combined and operating substantially as and for the purpose set forth.

14. The shaft a^{10} , and the gear-wheel A^{41} and ratchet-wheel A^{410} , both loose on said shaft, and the cam-wheel A^{400} , fixed thereon, the link connecting said loose wheels and engaged by the fixed cam-wheel, the dog P , engaging the ratchet-wheel, and the lever which operates the needle, engaging the dog to disengage the latter from the ratchet-wheel, all combined and operating substantially as set forth.

15. The vertical shaft a^{10} , having rigid with it the cam-wheel A^{400} , the washer A^{411} , carried at its lower end, the gear-wheel A^{41} , concentric with said shaft and cam-wheel A^{400} , and supported by the latter, the ratchet-wheel A^{410} , concentric with the shaft and supported by the washer, and having the eccentric slot a^{410} , the lever A^{412} , pivoted to the gear-wheel and engaged in the said slot, and having an abutment to be engaged by the cam wheel, and the dog P , to engage and detain the ratchet-wheel.

In testimony whereof witness my hand, in the presence of two witnesses, at Chicago, Illinois, December 23, 1885.

LA VERNE W. NOYES.
